12 Claims. (Cl. 204—108)

1

This invention relates broadly to improvements in machines and methods for refining metals electrolytically. Although the invention is particularly adapted to the refining of copper, it is also applicable to the electrolytic refining of other metals.

Heretofore, in the production of electrolytic copper, by either the series or multiple system, it has been customary to suspend the electrodes in the electrolyte and maintain them in a fixed, stationary position during electrolysis. This arrangement does not permit the electrolysis to be carried out in a continuous manner. A large number of tanks or cells and auxiliary equipment is required which take up a great deal of floor space. More space is used than necessary due to the lack of precision methods for maintaining minimum spacing and accurate alignment of the electrodes. Further, in practicing prior electrolytic refining methods, much labor is needed to inspect, handle and align the electrodes. The temperature of the electrolyte also must be kept low enough to permit men to work comfortably on top of the tanks. This is ordinarily below the temperature at which the electrolyte offers minimum resistance to the passage of electric current so that it is desirable to carry out the electrolysis at a higher temperature than that normally employed, in order to increase the current efficiency and effect a saving in power.

The principal object of this invention is to overcome the disadvantages of the conventional electrolytic refining systems and provide a machine and method whereby electrolysis may be carried out continuously to produce electrolytically refined metal. To this end, we have devised an improved machine wherein the electrodes are electrically connected in series and continuously advanced along through the electrolyte while maintained in accurate spaced alignment. Electrolyte which is heated to a high temperature is continuously circulated between the electrodes during electrolysis. The improved machine of this invention effectively reduces the current leakage past the electrodes and attains a much higher current efficiency than has been possible in prior electrolytic processes. Our invention also provides for continuous removal of the anode slimes formed during electrolysis. By utilizing the present invention the precious metal values in the anode slimes can be recovered immediately without having to wait until the electrolysis is completed and the electrodes removed as is the conventional practice.

Another object of the present invention is to

2

provide an improved machine and method for electrolytically refining metals which is efficient, economical to operate, and wherein precision methods for maintaining proper spacing and alignment of the electrodes are employed.

Another object of this invention is to devise an electroprocessing machine for refining metals which is substantially automatic and operable to continuously deliver electrolytic metal and recover slimes.

Another object is to devise a machine which utilizes the series system of electrolytically refining metal wherein the current input is on the order of that used in the multiple system.

Another object is to provide a machine of the character described wherein electrodes of the impure metal to be refined are placed in a tank or cell containing electrolyte and moved continuously therethrough from a loading to an unloading station while electrolysis takes place.

Another object is to provide a continuously operable machine for producing electrolytically refined copper which includes mechanism for lifting groups of moving electrodes out of the electrolyte, as required for effecting inspection, correction of deposits, washing, etc., while maintaining their relative position with respect to the remaining moving electrodes.

Another object is the provision of a machine for producing electrolytic metal which is capable of operating at much higher electrolyte temperatures and current densities than heretofore considered feasible.

Another object is to provide an improved electrolytic machine for refining metals having means operable in association with moving electrodes for gathering the slimes and effecting their removal simultaneously while electrolysis is in progress.

Another object of the present invention is to devise an electrolytic machine for refining metals wherein provision is made for moving the electrodes through the electrolyte while the latter is heated to a high temperature and wherein a minimum clearance is maintained between the individual electrodes and between the electrodes and the tank or container for holding the electrolyte. These provisions result in effecting a saving in labor and power and the current efficiency is markedly increased.

Still another object is to devise an improved process of electrolytically refining metals, such as copper, wherein the electrodes of impure metal are continuously moved along through the electrolyte during electrolysis. This reduces the ef-

fect of the anode and cathode polarization and permits the effective use of higher current input values than would otherwise be feasible in electrolytic refining processes of this character.

These and other objects and advantages will become apparent as the description proceeds. One embodiment of the invention is illustrated in the accompanying drawings and described as applied to the series electrolytic refining of copper. It will be understood, however, that this is merely illustrative and not limitative of the scope of our invention.

In the drawings:

Figure 1 is a diagrammatic plan view of an electrolytic machine for refining copper built according to this invention, showing the general layout of the tanks, arrangement of the electrodes therein and electrical connections thereto;

Figure 2 is a similar plan view of a single tank, partly broken away, showing the electrode rack advancing screw mechanism, bus bars, and gutters for collecting slimes with their drain apertures;

Figure 3 is an end elevation of a tank illustrating the general shape of the inner walls and bottom of the tank and showing the drive mechanism for the electrode rack advancing screws;

Figure 4 is a more detailed plan view of a tank taken at the loading end showing the electrode racks in place, a portion of one rack being broken away to show certain structural features more clearly;

Figure 5 is a cross-sectional view taken on the line 5—5 of Figure 4 and looking in the direction of the arrows;

Figure 6 is a detail view of the electrode and supporting rack means taken on the line 6—6 of Figure 5 and looking in the direction of the arrows;

Figure 7 is a detail sectional view taken substantially on the line 7—7 of Figure 6 and looking in the direction of the arrows;

Figure 8 is a view similar to Figure 6 taken on the line 8—8 of Figure 5 and looking in the direction of the arrows;

Figure 9 is a detail sectional view taken substantially on the line 9—9 of Figure 8 and looking in the direction of the arrows;

Figure 10 is a detail perspective view of one of the electrode hangers;

Figure 11 is a similar perspective view, partly broken away, of an electrode;

Figures 12 and 13 are detail perspective views, respectively, of the movable clamping plate means arranged at one end on each rack and the fixed end plate member disposed at the opposite end, showing their associated electrical connecting means for making contact with a bus bar;

Figure 14 is a cross-sectional view taken through a tank, similarly as in Figure 5, showing an electrode rack, with electrodes omitted, equipped with a slime removing attachment for sweeping the settled solids into side gutters for collection and removal;

Figure 15 is a plan view of the slime rack;

Figure 16 is a side elevational view of the same;

Figure 17 is a sectional view taken on the line 17—17 of Figure 15 and looking in the direction of the arrows;

Figure 18 is a front elevation of the traveling hydraulic crane for lifting and transferring racks of electrodes, the tank being shown in cross-section and the crane having part of the framework broken away and illustrated in position for raising a rack out of the tank;

Figure 19 is a side elevational view of the crane supported for movement on trackway at opposite sides of the tank; and

Figure 20 is a plan view section taken on the line 20—20 of Figure 18, showing one of the electrode supporting racks raised out of the tank and the crane connected at opposite sides of the tank to adjacent racks so as to travel therewith. The tank and racks are shown diagrammatically in the interest of clearness.

General construction

The electrolytic processing machine of this invention, in general, comprises one or more tanks 15 for holding electrolyte through which is moved electrodes formed of the impure metal to be electrolytically refined. The electrodes are assembled in racks and, during electrolysis, maintained accurately spaced and electrically insulated from each other by dielectric material. Multiple racks of electrodes are supported on conveyor means and moved as a unit at a predetermined rate of speed from one end of the tank to the other. During this continuous movement direct current is simultaneously conducted from one electrode to the next through the electrolyte to effect electrolysis. A traveling crane is operatively associated therewith to provide suitable mechanism for removing and replacing the racks of electrodes when inspection and correction of the deposit is required. Conventional means, not shown, is provided at opposite ends of the machine for handling the electrodes and loading and unloading the machine. Continuous and automatic removal 20 of the slimes formed during electrolysis is accomplished by means of a slime gathering attachment which is fastened to an electrode rack and passed through the tank.

Copper refining machine construction

Referring to the drawings in detail, wherein like reference characters designate similar parts throughout the various views, Figure 1 shows a preferred schematic layout of the tanks and electrical connections for a machine designed to produce electrolytic copper according to our invention. Two rows of tanks made up of three tandem arranged tanks are shown, designated A, B, C and A', B', C'. Any number of rows of tanks can be used as desired. A single tank may be substituted for the three tandem tanks, however, for practical reasons of tank construction, operation and electrical control, a minimum of three tanks is preferred. For elevating the racks of electrodes, 45 as required along the path of travel, to inspect and correct the cathode growth, a traveling crane means generally designated at D is arranged to travel along adjacent or over the tanks. Washing and inspection stations are provided between the tandem arranged tanks as diagrammatically illustrated at E.

Suitably shaped electrodes 25 formed by conventional methods from impure copper are assembled on supporting racks, generally designated 27. The electrodes are uniformly spaced lengthwise thereof, with minimum clearance being provided between the opposed edges of the electrodes supported on adjacent racks. The electrodes are maintained in this fixed spaced relationship, while the racks are moved along from one end of the tank to the other as a unit, at a definite rate of speed, with the electrodes suspended in electrolyte and electrically connected in series with a source of direct current.

75 Electrical connections made to the tanks are

such that the current distribution within a single tank will be a multiple series combination. A bus bar extends along at opposite sides of the tank and makes connection with the end electrode on each of the spaced racks. The total current from the bus bar is distributed to the plurality of racks and conducted to the electrodes by series arrangement. Preferably the current used is on the order of from 5,000 to 12,000 amperes per tank at an average voltage of between 15 and 30. The electrical energy supplied each tank and the rate of travel of the racks are correlated so that electrolysis of the electrodes will have been completed by the time they reach the end of the tank C or C'. A typical electrical connection for two rows of tanks is illustrated diagrammatically in Figure 1 wherein the bus bars 30 are connected to a direct current generator G by suitable electrical conductor means as indicated at 32. One or more generators or other sources of electric current may, of course, be utilized depending upon the size and number of tanks or electrolytic cells used.

Tank and electrode rack conveyor mechanism

Each of the tanks are similarly constructed and, as illustrated in Figures 2, 3, 5 and 14, are formed of concrete or steel 33 which is covered with electrical insulating material which is resistant to electrolytic attack, such as rubber, resin or the like as indicated at 34. The bottom of the tank is shaped to comprise a flat or crown surface 36 with side gutters 38 for collecting the slimes which are swept from the surface portion 36 during electrolysis. Drain openings 40 in the gutters communicate with the drain pipe means 41 which are suitably connected to slurry pumps, not shown, whereby the slimes are carried away for treatment. Inlet and outlet pipe connections 42 and 44, respectively, are provided as shown in Figures 5 and 14 for introducing and removing electrolyte. Conventional means, not shown, are also utilized to bring about circulation of the electrolyte and for maintaining it heated to the temperature at which minimum resistance is offered to passage of electric current.

The electrodes 25 are hung on the racks 27, as illustrated in Figure 5, and moved edgewise through the tank. Spacing of the electrodes is such as to give the maximum current efficiency. Due to the precision in mounting and conveying of the electrodes, the space between individual electrodes on each rack can be held to approximately one half inch or less, whereas the space between the edges of electrodes on adjacent racks may be on the order of one quarter of an inch. Sufficient space is left below the electrodes to provide for attaching a slime collecting rack. The continuous movement of the electrodes through the electrolyte effects a horizontal circulation of the electrolyte in addition to the vertical circulation between the electrodes caused by the change in specific gravity of the electrolyte during electrolysis and that brought about by mechanical means.

Suitable mechanism for moving the racks 27 is shown in Figures 4 and 5 and comprises the screw shafts 50 which are axially spaced to extend along the ledge at opposite sides of the tank. Screw follower means 52, as shown in Figure 5, is bolted to the outer ends of the racks 27 as indicated at 53, and is advanced upon rotation of the screw means. The screw shafts 50 are synchronously driven by motor 54, as illustrated in Figure 4, which is drivingly connected thereto through a reduction gear box 56, pinion 58, gear

60, and worm drive shaft 62. This latter shaft drives the axially spaced screw members by means of the spaced worm sections 63 which mesh with gear means 65 keyed respectively to the screw shafts 50. Journal bearing members 67 are provided adjacent the ends of the screw shafts and additional bearing means 69 are utilized to support the screw shafts intermediate the journals. In place of the screw drive mechanism shown, a rack and pinion means may be used to propel the electrode racks where greater tolerances are permissible.

Construction of the racks 27 and the manner of assembling the electrodes 25 thereon are illustrated in Figures 4, 5, 6 and 8. As shown in Figures 6 and 8, the racks comprise spaced channel frame members 70 of a length to span the tank, which are tied together at intervals by I-shaped web sections 72, the latter being preferably welded to the side walls of the channels as indicated at 74. This provides a rack which is sturdy and capable of supporting a group of electrodes without deformation. The depth of the I-shaped web members 72 is such that when welded in place, as illustrated in Figure 6, a space 76 is provided to accommodate the T-shaped hangers, generally designated 80, upon which individual electrodes are removably hung. For interlocking the hanger members with the rack, opposed strip means 82 is bolted or otherwise fixed to the inside of the channel members 70, as shown in Figure 6, forming a ledge for slidably engaging and retaining the ends of the hanger head portion 84.

Electrode hanger and clamping mechanism

Hangers 80, which support electrodes intermediate the ends of the rack, are formed of suitable dielectric material, such as hard rubber, synthetic resin, wood or the like, and shaped as illustrated in Figure 10. Spaced integral pin means 86 are provided on the depending body portion 88 of the hanger for fitting in apertures 90 of the electrode, as shown in Figure 11. The thickness of the body portion 88 of the hanger is preferably about half that of the head part 84 which is approximately double that of the electrodes. By shaping the hangers in this way the electrodes can be nested together as illustrated in Figure 9 and maintained properly aligned. Further, the hangers which are made of dielectric material operate to accurately space and electrically insulate the electrodes from each other as well as removably support the same on the rack. To prevent contact of the electrodes with the underside of the channel members 70, electrical insulating material is interposed therebetween as at 89.

Adjacent the clamping end of each rack, as shown at the left in Figure 5, a somewhat differently shaped hanger 94 is used to support the end electrode in order to make electrical connection with the end electrode from the bus bar 30. This hanger is shaped to receive a metal insert 96 and is provided with metal hanger pins 98 upon which the end electrode is supported, as depicted in Figure 7.

For firmly holding the group of electrodes together on each rack, suitable clamping means is provided as illustrated in Figures 4, 12 and 13. In Figure 12 an adjustable clamping assembly and electrical connecting means is illustrated and comprises a movable plate 100 having extended ear portions 101 in which are mounted bolt means 104. Ear portions 101 on the plate 100 work in slots 106 formed in the channel members 70 and

permit the plate to be moved toward or away from the fixed angle members 108 by advancing or retracting the nuts 109 on the bolts 104, as illustrated in Figure 4.

Electric current is passed to the end electrode through the member 110 from the bus bar by connection with the integral arm member 112. Arm member 112, as illustrated in Figure 12, is electrically insulated from metal plate 100 by means of the member 115. Preferably the arm member 112 is arranged to pass through apertures in the plate 100 and insulating member 115 as shown in Figures 5 and 12.

At the opposite end of the rack, as shown to the right on Figure 5, the end electrode forming a cathode is preferably made of pure copper, and normally is held at its uppermost portion against the metal plate 118 which plate is bolted to the channels 70 and electrically insulated therefrom, as indicated at 119 in Figure 4. The electrode hangers are clamped firmly against this fixed end plate by the adjustable plate 100 at the opposite end of the rack. Electric current is conducted from the end electrode to the adjacent bus bar 30 by way of the plate 118 and electrical conducting arm member 120, as illustrated in Figure 13.

Electrical connection between the bus bars and arm members 112 and 120 may be made by sliding contacts but in the preferred embodiment shown the metal bus bars 30 comprise elongated grooves 121 filled with mercury, as illustrated in Figure 5. Arm members 112 and 120 are arranged to extend over the mercury filled grooves 121 and make direct electrical contact with the mercury by means of the depending rod members 122. Slots 124 in the arm members 112 and 120 permit adjustment of the mercury contacting members 122. Suitable electrical cable connection is made to the ends of the bus bars, as shown at 126 in Figure 4, to conduct current to or from the same.

Roller support for electrode racks

To support the weight of the racks of electrodes and to provide for their movement therealong as a unit, each rack is equipped with rollers 130, one being arranged at each end. The rollers 130 are supported for movement on rails 132 which are mounted on top of the tank and extend along in the direction of its length as illustrated in Figures 4 and 5.

Suitable space is provided for accommodating the rail 132, bus bar 30 and associated mechanism at opposite sides of the tank beneath the channel member 70 as at 134 by reducing the depth of the channel portions projecting over the side walls of the tank as shown in Figures 5, 14, and 18. The bus bars 30 arranged at opposite sides of the tank are suitably insulated from the tank as shown at 135 and are secured in position by the insulating spacers 136 which are fastened to the rail 132, as shown in Figure 5.

Rollers 130 are mounted in a U-shaped casting assembly 137 as illustrated in Figures 5 and 8. The casting 137 is bolted to the channel members 70, as shown in Figure 8. The axle shaft of the roller is formed by an extension of the bolt 53 which passes through suitable apertures in the leg members 139. A nut 140 is threaded on the end of the bolt 53 to hold the parts together. By this construction the entire weight of the rack and electrodes is carried by the rails 132 and no bending stresses are placed upon the screw shaft which would interfere with its operation.

Lifting lugs 145 are provided at each end of the racks so that the racks can be readily grasped

by means attached to the crane 22 and lifted in and out of the tanks. Preferably the lugs 145 form an integral part of the casting 137 as shown in Figures 6 and 7. The casting is also provided with eyelet lug members 147 which are adapted to be engaged by suitable means on the traveling crane to lock it to the moving racks adjacent to the rack which is to be lifted out of the tank. In this way racks which are raised out of the tank continue to travel with the remaining electrodes whereby their relative position in the direction of travel is retained.

Slime rack mechanism

For effecting removal of the slimes which form during electrolysis and settle down on the bottom of the tank, a slime collecting means, such as illustrated in Figures 14, 15, 16 and 17 is utilized. This mechanism consists of a rectangular shaped frame means carrying plow blades and is adapted to be attached to an electrode rack and moved through the tank. In the embodiment shown, upright frame members 150 are rigidly attached at the top to the outer ends of an electrode rack and at their lower ends to the spaced interconnecting frame members 152. On the underside of the members 152 are mounted the plows 154 which are equipped with soft rubber wiper blade means 156 as illustrated in Figures 15 and 16. The end blade on opposite sides of the rack extends over the gutter 38 and comprises a depending blade portion 158 which engages therein. A central support for the blade rack may be provided where the width of the tank necessitates it. Such a support is illustrated in Figure 14, and consists of one or more tie rod members 160 which are attached at the bottom to the plate 162 and fastened at the top to the racks as shown at 164. To provide space for the central support 160 one electrode is omitted from the center of the rack. All parts of the slime collecting member which come in contact with electrolyte are protected by rubber or the like covering as indicated at 166. Movement of the slime collecting means through the tank operates to sweep the settled slimes from the surfaces 36 and 38 into drain openings 40 where they are carried off through the pipes 41 by means of a slurry pump, not shown.

Mechanism for handling the electrode racks

For removing the racks of electrodes from the electrolytic tanks, as required at intervals, a traveling crane such as illustrated in Figures 18, 19, and 20 is provided. The mechanism preferably is of the electric traveling crane type comprising suitable structural frame means 172 upon which is mounted spaced hydraulic cylinder lifting means 174, as illustrated in Figure 18. As shown, the crane is supported and arranged to travel on the rails 176 which extend along at opposite sides of the tank. To propel the crane, electric motor means 178 is geared to drive one of the pair of wheels 180 provided at opposite sides of the crane. Dual motor drive means is preferably used to produce a balanced, smoothly operating mechanism. Electrical energy is supplied to the crane operation motors through suitable overhead or side trolley wire connections as illustrated at 182 on Figure 19.

The hydraulic cylinders 174 on the crane 22 are operatively connected to the opposite ends of the beam 185 to the vertically reciprocable piston means 186. Beam 185 is supported for movement between the end frame columns 188 and overhead

bridge structure 190. To guide the movement of the elevating beam 185 suitable rack and pinion means 192 and 194 respectively are provided as shown in Figures 18 and 19. Pivoted hooks 200 carried by the reciprocable beam 185 are spaced to engage the pins 202 of the lugs 145 fastened at the opposite ends of the electrode racks. The hooks 200 are operatively connected to the lifting pins 202 when they are swung from the dotted line position depicted in Figure 18 to the full line position. Mechanical leverage means is employed to control the position of the hooks. Suitable mechanism for accomplishing this is shown in Figure 18 wherein adjustable link means 206 is arranged to swing the hooks 200 in and out of engagement with the pins 202. The link members 206 are secured at their opposite ends to a lever 208 which is pivoted intermediate its ends as at 209. Movement of the lever about its pivot is effected by means of a hydraulically operated piston and cylinder means 210 which is mechanically connected to the lever 208 by means of the piston rod 212 and link 214. It will thus be seen that reciprocation of the piston rod 212 and connecting link 214 shifts the lever 208 about its pivot to swing the hooks 200 inward or outward as desired.

The hooks and operating mechanism including the piston cylinder 210 is mounted on the movable beam 185. Flexible conduit means 216 is used to connect the cylinder 210 to the central controlled valve 218 which is positioned adjacent the operator's station on the platform 220, as illustrated in Figure 20. Fluid-like pressure is supplied from a suitable source, not shown, and is connected to the valve 218. Hydraulic pipe connections 222 and 223 are connected to the hydraulic cylinders 174 which raise and lower the beam 185.

To interlock the traveling crane 22 with the moving electrodes when it is desired to elevate a particular rack of electrodes out of the tank, rocker shaft means 227 is mounted on opposite sides of the crane adjacent the ends of the racks as shown in Figure 20. Arm members 229 are attached to the rocker shafts and are spaced so that their respective end lug or hook portions 230 will engage in the eyelets 147, when the rocker shaft is actuated to swing the arms downwardly from a raised position, as illustrated in Figure 18. Each pair of arm members 229 are arranged to interlock with the eyelets 147 on spaced racks, as shown in Figure 20, whereby the intermediate rack is free to be raised out of the tank for inspection and adjustment and lowered back in its place while the crane and racks of electrodes move along as a unit. Each of the rocker shafts 227 is provided with actuating means consisting of a motor 232 which is operatively connected through a gear 234 on the rocker shaft whereby the respective rocker shafts can be rotated to swing the attached arm members 229 in or out of locking engagement with the racks. A reversing motor is preferably used for this purpose, which is arranged to be controlled from the operator's station on the platform 220.

Operation

In the production of electrolytic copper in accordance with this invention, electrodes of impure copper, which are to be bipolar are coated on the cathode face, in the conventional manner, to permit the copper deposit to be readily stripped from the unrefined portion at the end of the process. The electrodes are assembled on the racks in spaced, electrically insulated arrangement be-

- tween anode and cathode electrodes as hereinbefore described, and positioned in the tanks filled with electrolyte. Electrical current connections are made to the racks as described and the screw drive conveyor operated to move the electrodes along through the solution from one end of the tank to the other. During this movement the electrolyte, which is heated to a high temperature, is circulated through the tanks.
- 5 During normal operation, the tanks are kept full of electrodes. When a rack of electrodes is removed from one end of a tank, another rack is introduced at the other end to provide a continuous electrolytic process.
- 10 The electrodes intermediate the end electrodes on the racks are bipolar. Impure metal, on the side from which the current leaves, is dissolved while pure copper is deposited on the other side. As the electrolysis proceeds and the electrodes are
- 15 conveyed through the three tanks in tandem, the electrolyte level in each tank is adjusted to leave a certain portion unrefined as a support for the newly deposited metal.
- 20 Slimes which gradually accumulate on the bottom of the tank are continuously swept into the gutters provided to receive the same by a slime gathering means which is suitably fastened to an electrode rack and moved through the tank. The electrodes are continuously advanced from the
- 25 loading end of the tandem arranged tanks to the washing and unloading station at the end of the last tank. Thereafter the electrodes are stripped of electrolytically deposited copper and the scrap returned for reworking. Inspection of the electrolytic deposit is made at intervals during electrolysis, and the traveling crane is used to elevate the racks for this purpose.
- 30 In the preferred embodiment of our invention, as illustrated and described in detail, all the electrodes are supported for movement through the electrolyte. A modification of the arrangement illustrated is, however, contemplated wherein the intermediate bipolar electrodes are moved while the end electrodes constituting the anode and
- 35 cathode remain stationary. In this alternative construction the electrical connections to the anode and cathode electrodes may be of the conventional type in place of the mercury type shown.
- 40 It will be understood that we desire to comprehend within our invention such other changes and modifications as may readily suggest themselves to those skilled in the art and which come within the scope of the appended claims.
- 45
- 50
- 55 We claim:
1. A machine for use in the production of electrolytic copper which comprises a tank for holding copper electrolyte solution, racks arranged crosswise of said tank at spaced intervals throughout the length of said tank, hangers disposed on said racks for supporting electrodes, said electrodes being formed of impure copper and suspended from said hangers which are carried by the racks, said hangers comprising an accurately shaped body portion formed of dielectric material which abuts against the adjacent hanger from which an electrode is suspended when the hangers and attached electrodes are compacted on a rack retaining the electrodes
- 60 fixedly and accurately spaced from each other a predetermined distance, means on said rack for clamping said hangers together to form a compact group, conveyor means comprising a pair of axially spaced screw members which are synchronously driven, screw followers attached at
- 65
- 70

the opposite ends of each rack operatively connected to said screw members, a motor and associated gear reducing means for synchronously driving said screw members to advance said racks as a unit in a continuous manner from one end of said tank to the other, means for electrically connecting the first and last electrodes on each rack of electrodes to a source of direct electric current and passing electric current to said first electrode and through the electrolyte to each electrode in series to said last electrode on the rack continuously as said racks of electrodes are moved along through the electrolyte to cause electrolysis to take place and the electrodes between the first and last on each rack to become bi-polar electrodes with the surface facing toward said first electrode being cathodic and the opposite surface facing toward said last electrode being anodic and causing said bi-polar electrodes to corrode away and the copper to pass into solution in the electrolyte and be electrodeposited out on the cathode surface of the adjacent electrode.

2. An electrolytic machine for refining impure metal electrodes by electrolysis comprising a tank for holding electrolyte, a rack spanning said tank, metal electrodes to be electrolytically refined spacedly supported on said rack and arranged for suspension in the electrolyte in the tank, said rack comprising an anode and cathode with intermediately spaced electrodes of impure metal, means for electrically connecting the anode and cathode electrodes on said rack to a source of direct electric current and passing electric current to the anode and through the electrolyte to each of the spaced intermediate electrodes solely through the electrolyte in series to said cathode, means for moving said rack of electrodes as a unit from one end of said tank to the other, and means for conducting electric current to the electrodes on the rack continuously as the same is moved from one end of the tank to the other.

3. An electrolytic machine for refining impure metal electrodes by electrolysis comprising a tank for holding electrolyte, a plurality of racks spanning said tank, each of said racks comprising an anode and a cathode with intermediately spaced electrodes of impure metal to be refined spacedly supported on the rack and arranged for suspension in electrolyte in the tank, means for electrically connecting the anode and cathode electrodes on the respective racks to a source of direct electric current and for passing electric current from the anode and through the electrolyte to each of the spaced intermediate electrodes on a rack solely through the electrolyte in series to the cathode, means for moving said racks of electrodes as units from one end of said tank to the other, means for conducting electric current to the electrodes on the racks continuously as same are moved from one end of the tank to the other, and crane means operatively associated with said rack moving mechanism for elevating and lowering a selected rack of electrodes while maintaining its relative horizontal spacing between adjacent racks and while continuing the movement of the racks of electrodes from one end of the tank toward the other.

4. An electrolytic machine for refining impure metal electrodes by electrolysis comprising a tank for holding electrolyte, a plurality of spaced racks spanning said tank, metal electrodes to be electrolytically refined spacedly supported on said racks and suspended in the electrolyte contained in the tank, each of said rack of electrodes com-

5 prising anode and cathode electrodes with intermediately spaced electrodes of impure metal all carried by said rack and arranged for suspension in electrolyte in the tank, means for electrically connecting the anode and cathode electrodes on said racks to a source of direct electric current and passing electric current from anode to electrolyte and to each of the spaced intermediate electrodes on each rack solely through the electrolyte in series to the cathode, means for moving said plurality of spaced racks of electrodes as a unit from one end of said tank to the other, and means for conducting electric current to the electrodes on the racks continuously as the same are moved along from one end of the tank to the other.

20 5. An electrolytic machine for refining impure copper electrodes by electrolysis comprising a tank for holding electrolyte, a rack spanning said tank, anode and cathode electrodes with intermediately spaced electrodes of impure copper to be electrolytically refined supported on said rack, said electrodes being arranged for suspension in electrolyte in the tank, means for electrically connecting the anode and cathode electrodes on said rack to a source of direct electric current and for passing electric current from anode to the intermediately spaced impure copper electrode means and thence to cathode solely through the electrolyte in series, means for moving said rack of electrodes as a unit from a loading to an unloading station in said tank, and means for conducting electric current to the electrodes on the rack continuously as the same is moved along through said tank.

40 6. An electrolytic machine for refining impure copper electrodes by electrolysis comprising a tank for holding electrolyte, a rack spanning said tank, anode and cathode electrodes with intermediately spaced electrodes of impure copper to be electrolytically refined supported on said rack, said electrodes being arranged for suspension in electrolyte in the tank, means for electrically connecting the anode and cathode electrodes on said rack to a source of direct electric current and passing electric current to the anode through the electrolyte to the intermediately spaced impure copper electrode means solely through the electrolyte in series to the cathode, means comprising a pair of screw shafts operatively connected to the opposite ends of said rack for moving said rack of electrodes as a unit from a loading to an unloading station in said tank, means for synchronously driving said screw shafts, and means for conducting electric current to the electrodes on the rack continuously as the same is moved along in said tank.

50 7. An electrolytic machine for refining impure copper electrodes by electrolysis comprising a tank for holding electrolyte, a rack spanning said tank, anode and cathode electrodes with intermediately spaced and electrically insulated electrodes of impure copper supported on said rack and arranged for suspension in electrolyte in the tank, means for electrically connecting the anode and cathode electrodes on said rack to a source of direct electric current and passing electric current from the anode through the electrolyte to the intermediately spaced electrodes solely through the electrolyte in series to the cathode, means for moving said rack of electrodes as a unit from one end of the tank to the other, slime gathering means arranged in said tank and movable therethrough concurrently with said rack for removing the slimes produced during elec-

trolysis, and means for conducting electric current to the electrodes on the rack continuously as the same is moved from one end of the tank to the other.

8. An electrolytic machine for producing electrolytic copper by electrolysis comprising a tank for holding copper sulphate electrolyte solution, a rack spanning said tank, anode and cathode electrodes with intermediately spaced electrodes of impure copper carried by said rack and arranged for suspension in the electrolyte in the tank, scraper means positioned in said tank engageable with the bottom of said tank and operable to move the slimes which gradually accumulate on the bottom of the tank during electrolysis into drain means in said tank for removal, means for electrically connecting the anode and cathode electrodes on said rack to a source of direct electric current and passing current to the spaced impure copper electrodes solely through the electrolyte in series to cathode electrode, means for moving the rack of electrodes and slimes scraper as a unit from one end of the tank to the other and means for maintaining the electrodes connected to said direct current source while said rack of electrodes is being moved along from one end of the tank to the other.

9. The process of electrolytically refining copper by electrolysis which consists in suspending anode and cathode electrodes with intermediately spaced electrodes of impure copper in copper sulphate electrolyte solution, maintaining said electrodes accurately spaced and electrically insulated from each other except through the electrolyte, passing direct electric current to the anode electrode and to said intermediately spaced impure copper electrodes in series to the cathode, moving all of said electrodes as a unit along through the electrolyte from a loading to an unloading station, continuously circulating fresh electrolyte about said electrodes and withdrawing the slimes formed during electrolysis simultaneously as the electrodes are moved along and the electrolysis proceeds, said electrolysis being continued during movement of the electrodes until the impure copper electrodes have been substantially replaced by electrolytic copper.

10. In the process of electrolytically refining copper by the series system using anode and cathode electrodes with intermediately spaced electrodes of impure copper, the step of continuously moving the electrodes through the elec-

trolyte from one end of the electrolytic cell to the other while simultaneously effecting electrolysis of the impure copper electrodes by passing electric current from the anode to the impure copper electrodes solely through the electrolyte in series to the cathode.

5 11. In the process of electrolytically refining copper by the series system wherein anode and cathode electrodes together with intermediately spaced electrodes of impure copper are placed in electrolyte and subjected to electrolysis, the steps comprising supporting and moving all the electrodes as a unit through the electrolyte, circulating electrolyte between the electrodes and concurrently removing the slimes formed during electrolysis as the electrodes are moved along through the electrolyte and subjected to electrolysis.

10 12. In an electrolytic cell for effecting series electrolysis to refine metals, the combination of an electrolytic cell for depositing metal, an anode, a cathode, intermediate bipolar electrodes formed of impure metal to be refined, means arranged over said cell for suspension of the electrodes in the electrolyte contained in said cell, hangers on said suspension means for independently supporting the electrodes in spaced relationship and electrically insulated from each other except through the electrolyte, means for connecting the electrodes in series with a direct current source 20 of electricity to cause electrolysis to take place and the bi-polar electrodes to corrode away and the metal to go into solution in the electrolyte and electroplate onto the cathode surface of the next adjacent electrode, and means for moving the bi-polar electrodes horizontally through the cell as electrolysis proceeds.
